CONTROL INSTRUMENT CASING

Carl G. Kronmiller, Edina, Minn., assignor to
Minneapolis-Honeywell Regulator Company,
Minneapolis, Minn., a corporation of Delaware

Application December 23, 1948, Serial No. 150,341

Term of patent 14 years

(Cl. D52—7)

To all whom it may concern:

Be it known that I, Carl G. Kronmiller, a citizen of the United States, residing at Edina, in the county of Hennepin and State of Minnesota, have invented a new, original, and ornamental Design for a Control Instrument Casing, of which the following is a specification, reference being made to the accompanying drawing, forming part thereof, and in which

The single figure of the drawing is a perspective view of a control instrument casing embodying my new design as viewed from the left and from above.

The dominant features of my design reside in the portions shown in full lines.

I claim:

The ornamental design for a control instrument casing, substantially as shown and described.

CARL G. KRONMILLER.
